UNITED STATES PATENT OFFICE

91,116

DESIGN FOR A KNIFE SET HOLDER OR SIMILAR ARTICLE

Benjamin F. Lee, Niagara Falls, N. Y.

Application September 13, 1933. Serial No. 49,242

Term of patent 7 years

To all whom it may concern:

Be it known that I, BENJAMIN F. LEE, a citizen of the United States, residing at Niagara Falls, Niagara County, State of New York, have invented a new, original, and ornamental Design for a Knife Set Holder or Similar Article, of which the following is a specification, reference being had to the accompanying drawing forming a part thereof.

In said drawing:

The figure is a perspective view of a knife set holder embodying my design.

I claim:

The ornamental design for a knife set holder or similar article, substantially as shown.

BENJAMIN F. LEE.
